(57) **CLAIM**

The ornamental design for a speed loader for a revolver style firearm, as shown and described.

DESCRIPTION

FIG. 1 is a front perspective view of the speed loader for a revolver style firearm shown in an opened position;

FIG. 2 is another front perspective view thereof;

FIG. 3 is a rear perspective view thereof;

FIG. 4 is a rear elevation view thereof;

FIG. 5 is a left side view thereof;

FIG. 6 is a right side view thereof;

FIG. 7 is a front elevation view thereof;

FIG. 8 is a top plan view thereof;

FIG. 9 is a bottom plan view thereof; and,

FIG. 10 is a rear perspective view thereof showing the Speed Loader for a revolver style firearm in a latched position with a plurality of bullets shown in broken lines forming no part of the claimed design.

The broken lines shown in the drawings illustrate features of the article to which the design is applied or in which the design is embodied that form no part of the claim.

1 Claim, 8 Drawing Sheets
